A. McR. BLAIN, OF DEERFIELD, VIRGINIA.

Letters Patent No. 65,534, dated June 11, 1867.

IMPROVED APPLE-PARING, CORING, AND SLICING MACHINE.

The Schedule referred to in these Letters Patent and making part of the same.

TO ALL WHOM IT MAY CONCERN:

Be it known that I, A. McR. BLAIN, of Deerfield, in the county of Augusta, and State of Virginia, have invented a new and useful Improved Machine for Paring, Coring, and Slicing Apples; and I do hereby declare that the following is a full, clear, and exact description thereof, which will enable others skilled in the art to make and use the same.

The present invention relates to a machine for the paring, coring, and slicing of apples more particularly, although it can be used for other and various fruits, by means of which machine each and all of the operations above stated can be performed in the most easy and perfect manner. In the accompanying plate of drawings, my improved machine is illustrated—

Figure 1 being a plan or top view of the same; and

Figure 2 an elevation of a portion of one side of the machine.

Similar letters of reference indicate like parts.

A, in the drawings, represents the framework of the machine, which is to be of any suitable construction to accommodate its various working parts. B, a horizontal shaft or spindle, extending across the framework of the machine, in bearings of which it turns. On one end of this shaft is secured a fork or prong piece, C, to receive the apple to be pared, which is accomplished by revolving the shaft B, at the same time holding a paring-knife blade, D, up and against the same, this blade being secured to a handle, E, for convenience in holding it to the apple. To revolve the shaft B, a crank-handle, F, is attached to it, at the opposite end to that having the fork or prong piece C. After the apple is pared as above stated, it is placed upon the table or platform portion G of the machine, where it is cut at right angles with the stem and seed-pods into two parts, or, in other words, halved, by bringing down the knife-blade H attached to a handle-lever or arm, I, hinged to the frame A, so as to swing or play up and down in a vertical plane; this arm I being thrown up after it has been depressed by the action of the bent spring J properly arranged therefor, in connection with it. The apple having been thus halved, is then cored by placing it with its two halves together upon and against the end piece J² of a horizontal frame, K, arranged to slide in the framework A across the same, which end piece J² is open in its centre, through which projects a tool, L, suitable for removing or cutting the core from an apple. This tool is at one end of a transverse horizontal shaft, N, which is revolved through a pulley and belt connection with the prong-shaft B', the pulley on the coring-tool shaft being loose, and being thrown into and out of connection with the shaft by means of a clutch, N, arranged to slide upon such shaft. The point of the coring-knife L is intended to cut out only the stem of the apple, and the angular part to cut out the seed-pods which diverge from the centre of the apple, and thus avoid the waste incident upon cutting a piece of the same diameter as the seed-pods entirely through the centre of every apple, as in other machines. The apple, after being thus cored, is removed from the frame K, which is immediately thrown back by the action of the bent spring P properly arranged in connection with it therefor. To slice or divide the apple up into a series of pieces, it is then placed upon the upright spindle S of the framework A, under the handle of the halving-knife, resting upon the intersecting knife-blades T, secured or arranged in the framework A, when, bringing such handle down upon the apple, it is then cut or divided into parts corresponding to the number of said knife-blades T, as is obvious without any further explanation, the several pieces of the apple passing through the spaces between the knife-blades down into a chamber or box formed in the lower portion of the framework A for their reception.

I claim as new, and desire to secure by Letters Patent—

1. The coring-blade L, shaft M, clutch pulley N, and bent spring P, in combination with the horizontal frame K, framework A, and prong-shaft B, constructed and operating substantially as herein shown and described.
2. The arrangement of the prong-knife B, halving-shaft H, coring-knife L, and slicing-blades T with each other, and with the frame A, when all are constructed and operating as herein described and for the purpose specified.

The above specification of my invention signed by me this 12th day of May, 1866.

A. McR. BLAIN.
